SWITCH CONTACT

William J. Shore, New York, N. Y.

Application March 28, 1935, Serial No. 13,421

7 Claims. (Cl. 173—332)

My invention relates to switch contacts for making electric contact between two parts, one of which may be stationary and the other removable, such, for example, as the contacts or contact surfaces for knife, plug or fuse switches or contacts.

In switches of the above type a movable contact surface, such as the sides of a knife switch or of a plug, has been brought into contact or between yielding surfaces with a view to insuring a tight contact even though the parts be displaced or become worn.

In the switches, as heretofore constructed, the yielding parts have yielded in only one direction or about a single pivot; consequently if the member that is brought into contact or inserted between the yielding elements becomes displaced or twisted in a direction other than that provided for by the yielding of the contact elements, the closeness or tightness of contact will be impaired and a large part of the contact surface may be spaced from or diverge from the yielding elements. In such cases the resistance through the switch element is greatly increased reducing its efficiency and creating heat which causes rapid deterioration.

In switches of the above type an arc tends to form as the removable element is withdrawn. In switches heretofore constructed this arc tends to form between the contact surfaces resulting in pitting or building up of deposits which impair the contact surface and increases the resistance through the switch contacts.

These various disadvantages are avoided in my present invention which provides yielding contact surfaces that yield in several directions so as to adapt themselves to various displacements of the movable contact element, and which also shift the point of departure of the removable contact when being withdrawn from the fixed contact surface so as to displace the arc to surfaces other than the contact-making surfaces.

Various features of the invention are illustrated in the accompanying drawings in which Fig. 1 is a longitudinal section showing half of a contact switch of the plug type embodying a preferred form of the invention; Fig. 2 is a longitudinal sectional view taken at a right-angle to the view of Fig. 1; Fig. 3 is a cross-section on the line 3—3 of Fig. 2; Fig. 4 is a perspective view of a pair of plug-receiving contact elements; Fig. 5 is a plan view of a blank from which the contact-receiving elements of Fig. 4 may be formed; Figs. 6 and 7 are detail sectional views similar to that of Fig. 2 and on an enlarged scale

showing the displacement of contact as the contact element is inserted and removed from between the receiving contacts; Fig. 8 is an enlarged detail side view of a portion of a contact embodying my invention; Fig. 9 is an enlarged longitudinal section taken on a plane similar to that of Fig. 2 and showing the yielding of the contact elements to adjust themselves to displacements of a plug from its normal position between the contact surfaces; Fig. 10 is a cross-section similar to that of Fig. 3 on an enlarged scale showing the normal displacement of the contact surface upon insertion of a plug in proper position; Fig. 11 is a view similar to Fig. 10 but showing the twisting of the contact blades to adjust themselves to a displacement of the plug from its normal position; Figs. 12, 14, 15 and Figs. 13, 16 and 17 are vertical side elevations and horizontal cross-sections of various modifications of the contact surface elements; Fig. 18 is a side view of a knife switch embodying the invention; Fig. 19 is a vertical section of the knife switch taken on line 19—19 of Fig. 18; Fig. 20 is a view similar to that of Fig. 19 of a different embodiment of the invention; Fig. 21 is a plan of a blank from which the contact element of Fig. 19 may be stamped; Fig. 22 is a plan of a blank from which the switch contact of Fig. 20 may be stamped; Fig. 23 is a plan view of a fuse having contact ends embodying the invention, and Fig. 24 is a plan of a blank from which the contacts of Fig. 23 may be stamped.

In my invention I provide a contact element of sheet metal of suitable strength and thickness from which a number of contact wings are offset toward the position to be occupied by a movable or insertable terminal, such as a knife or plug. The offset wings are integral at one edge with the plate from which they are stamped, preferably at an edge transverse to the direction in which the knife or plug is to be inserted so that they may swing about this edge as a pivot.

The wings are rounded or curved convexly toward the inserted knife or plug so as to present a tangent surface to the latter in various positions of displacement of the wings. The wings are also narrowed somewhat at the edge where they join the supporting strip from which they are pressed so that they may twist or deflect slightly on an axial line parallel or longitudinal to the line of insertion of the blade or plug. Consequently any sidewise displacement or tilting of the blade or plug on a line transverse to its length will be accommodated by a springing inwardly or outwardly of the several wings, and any twisting or

warping of the blade or plug about a longitudinal axis is accommodated by a slight twisting of the wings, it being understood that these wings tend to take the normal position but are readily displaceable therefrom against their spring action by the plug or blade.

Several such wings are provided upon each contact surface or contact-receiving element so that a large number of tangent contacts may be made. 10 Normally the wings tend to swing away from their point of support and as the blade or plug is swung into contact they are displaced. As the blade leaves the contact the wings tend to close over the end edge so that the last contact is nearer 15 to the base of the wings than their contact surface and the arc tends to form at this point rather than at the contact-making surfaces of the wings.

Referring more particularly to Figs. 1 to 5 of the drawings, the invention is shown as applied to a common type of socket and plug connection, such as is used for flat irons and similar purposes.

In this embodiment, a pair of contact blades 1 and 2 are mounted in a plug 3, preferably 25 formed in two halves, bolted together by means of a bolt 4 and containing binding posts 5 and 6 to connect the blades 1 and 2 respectively to the wires of a cable 7. The blades 1 and 2 project from the end of the plug 3 and are insertable 30 in recesses 8 and 9 of a socket element 10 which also may be formed of a pair of halves joined by bolts 11. Each of the recesses 8 and 9 is provided with a pair of contact-receiving plates 12 of identical construction and arranged in opposed or 35 mirror image relation as shown in Figs. 2 and 4. The plates 12 are joined at their upper end 13 and are secured at this end by means of a binding screw 14 which connects them to the wires of a cable 15.

40 As shown in the above figures, and also in larger scale in Figs. 6 to 11 inclusive, each of the contact plates or elements 12 is provided with a number of wings 16 which project inwardly toward each other so as to grip blades 1 and 2. 45 The wings 16 are curved convexly toward the blade 1 and normally extend toward each other to a distance less than the thickness of the blade, as indicated in Fig. 6. When the blade 1 is inserted the wings are spread apart against their 50 tension and thus form a resilient close sliding contact with the sides of the inserted blade. The position of contact varies with the thickness of the blade, but in all displacements of the blade it occurs at the rounded surface of the wing so that 55 there is at all times a tangent contact.

Inasmuch as there are several wings for each receiving contact, a relatively large aggregate area or line is provided while still preserving a line or tangent contact thereby insuring a tight 60 or close contact throughout. This would be much more difficult, if not impossible, if it were attempted by a single continuous line contact.

It will be noted, moreover, that the normal contact line when the blade is inserted is at the 65 level X-X, Fig. 7, but as the contact is displaced and the blades gradually close the level of contact lowers to that of Fig. 6, or even lower, and the blade is separated from the wings at the lower level indicated in Fig. 6. Any arcing that may 70 take place is, therefore, at this lower level and away from the normal contact surface so that the latter is preserved from pitting or burning or deposition of metal.

In order to strengthen the supporting surface 75 of the contact plates 12 from which the wings 16

diverge, the edges of these wings are offset as at 17 thereby forming in effect a channel or Z-shaped construction at each edge of the elements 12 between the intermediate part 18 that connects these channel elements between the wings. 5

The transverse width of the wings 16 at their base where they join the intermediate part 18 is of a dimension not exceeding the width of the intermediate part 18 and preferably somewhat less; whereas the free part of the wings is wider 10 having been formed from metal of the displaced part 17 before the displacement of the latter. This may be accomplished by stamping the contact elements 12 from a blank, such as that shown in Fig. 5, in which trapezoid cuts are formed for 15 the wings 16 and the offset part 17 is thereafter formed by bending on the longitudinal lines 19 and 20, the line 19 being at the base or narrow dimension of the trapezoid and the line 20 at its wider point. 20

The part of the stamp between the pair of contact surfaces 12 is narrowed to form the neck portions 21 and 22 which may be folded on the transverse line 23 to bring the parts 12 into opposed position, the blank being also bent or offset 25 on the lines 24 and 25 to provide the proper spacing. The neck portions 21 and 22 are provided with openings 26 which align when the blank is bent on the line 23, and the neck 22 is provided with side flanges 27 that form the end 30 closing flanges 28 of the finished element as shown in Fig. 4.

By having the base part of the wing 16 narrowed, it is given a limited flexibility in a transverse direction so that it may twist to accommodate itself to the warping or twisting of the blade 1 or 2. In this way the wings may accommodate themselves to sidewise warping or twisting as well as to displacements sidewise or inclined to their true or proper longitudinal position. This is 40 illustrated in Figs. 9, 10 and 11.

Fig. 9 shows the accommodation of the wing 16 to contact with opposite surfaces of the blade 1 inserted in a position slightly oblique to the longitudinal. At the lower part of the contact-receiving socket the wing is displaced still further from its normal contact position, but this has only the effect to slightly lower the line of tangent contact to the position shown by the dotted line 29. The opposite wing is not pressed back as far, 50 and the tangent line will be at 30. The intermediate wings hit the blade at about the normal position and the upper wings are displaced in the opposite sense from the lower, the right-hand contact line 31 being lower than the left-hand contact line 32. The accommodation of the wings to twisting or warping is shown in Figs. 10 and 11, in which Fig. 10 shows the normal position of the blade 1 and the normal displacement of the wings 16; whereas Fig. 11 shows, in somewhat 60 exaggerated manner, the effect of a sidewise warping which is accommodated by a twisting of the wings 16. 55

Figs. 12 and 13 show a still further modification of the wing construction in which the offset portion at the side edges of the contact elements are not only offset but double back on each other in a reverse bend 33 to give a spring action about a longitudinal axis at about the center point of the wings. It will be obvious that this will provide a much more flexible twisting and accommodation to warping. A somewhat similar effect is obtained in the modification shown in Fig. 14 by the sidewise slits 34 which narrow the point or area of twisting. 70 75

In the modification shown in Figs. 15 and 16, the wings 16 are slit longitudinally as at 35 at their center points to permit them to grip a cylindrical plug or insert 36, as shown in Fig. 16. A sidewise displacement of the plug 36 will still enable effective contacts to be made on a number of wings.

The modification shown in Fig. 17 is similar to that of Figs. 1 to 11 except that instead of having an offset 17 or a Z or channel or flange construction, the edges are bent inwardly as at 37 to enclose the wings and plates. This has the advantage of spacing the wings and their supporting plates at a proper pre-determined position.

Figs. 18, 19 and 20 show an embodiment of the invention as applied to a knife switch. In this construction the contact blade 38 is pivoted at one end to an upright 39 mounted on an insulating base 40. The blade is movable on the pivot 39 by means of an insulating handle 41 so as to bring it between a pair of contact terminals or plates 42 and 43 from which the wings 16 spring inwardly, as described in previous modifications.

The plates 42 and 43 are reinforced and strengthened against sidewise displacement by means of sidewise abutments 44 and 45. In the modification shown in Fig. 19 these abutments are formed from a stamping having the trapezoidal cuts to form the wings 16 and shaped to provide a base 46 from which the plates are bent on lines 47 and 48, and from the latter the reinforcements or abutments 44 and 45 are bent on lines 49 and 50.

A stop 51 for the blade 38 is provided by bending in a tongue from one end of the plate 42.

In the modification shown in Fig. 19 the plates 42 and 43 are secured by a bolt 52 in the base 46. The modification shown in Fig. 20 differs in that the contact elements are secured by a pair of bolts 53. These bolts fasten in ears 54 bent from the sidewise abutments 44 and 45.

Fig. 23 shows the invention as applied to a fuse 55 having end contact plates 56 and 57 that are insertable between terminal elements 58 and 59 respectively, similar in construction to those shown in Figs. 19 and 20 but differing only in that they are secured to the base 60 by means of bolts 61 passing through a sidewise extension 62 from the base 46.

By the above invention, therefore, I have provided a contact device in which a contact-making surface may be deflected in a transverse direction and may also twist to accommodate itself to deflection or warping in the terminal with which it is to make contact.

The invention also provides a number of tangent or line contacts in all positions of the terminal and contact element. Moreover, the convex surface of the contact-making parts combined with the spring action causes the terminal to break contact at a different part of the surface from the contact-making area. Consequently, if an arc is formed it will not be formed at the contact-making area and, therefore, will not burn or pit or otherwise injure the contact surface. Moreover, the contact element may be

readily and easily formed by simply cutting and stamping a piece of sheet metal and, therefore, provide a very inexpensive construction.

What I claim is—

1. A contact having a space into which a contact blade may be inserted and a contact plate in said contact having wings integral with and sprung from the face of said plate toward a position of contact with an inserted blade, said wings being convex toward said blade and spaced at successive intervals along the direction of insertion of said blade.

2. A contact having a space into which a contact blade may be inserted and a contact plate in said contact having a succession of parallel wings sprung from the surface of said plate toward a position to contact with an inserted blade, said wings being integral with said plate at one of their edges and being convex toward an inserted blade and spaced at successive intervals along the direction of insertion of said blade.

3. A contact having a space into which a contact blade may be inserted, a pair of spaced plates on opposite sides of said blade receiving space and wings sprung inwardly from the opposed surfaces of said plates toward a position of contact with an inserted blade, said wings being convex toward such inserted blade and spaced at successive intervals along the direction of insertion of said blade.

4. A contact having a space into which a contact blade may be inserted and having a metallic plate facing said space, said metallic plate having wings of trapezoid shape, cut and stamped therefrom with the smaller of the parallel edges of said wings integral with said plate, said wings being convex toward a blade inserted into said space.

5. A contact having a space into which a contact blade may be inserted and having a metallic plate facing said space, said plate having its side edges flanged toward said space and having integral wings sprung from a face of said plate into a position to contact with an inserted blade, said wings being convex toward an inserted blade.

6. A contact having a space into which a contact blade may be inserted, a pair of spaced plates stamped from a single sheet bent to space said plates on opposite sides of said blade receiving space, said plates having contact wings sprung from the opposed surfaces to a position to contact with said inserted blade, said wings being integral with said plates at one of the edges of the respective wings and being convex to the inserted blade and spaced at successive intervals along the direction of insertion of said blade.

7. A contact having a space into which a contact blade may be inserted and having a metallic plate facing said space, wings stamped from said plate and integral at one edge therewith and convex to an inserted blade, said wings having slots extending from the sides of the wings at said integral edge toward the center lines of said wings to narrow the connection of said wings to said plate.

WILLIAM J. SHORE.
